UNITED STATES PATENT OFFICE.

JAMES MORRIS O'KELLY, OF NEW YORK, N. Y., ASSIGNOR OF ELEVEN-TWENTIETHS TO GEORGE D. BAYAUD, OF SAME PLACE.

AUTOMATIC VENDING APPARATUS.

SPECIFICATION forming part of Letters Patent No. 396,228, dated January 15, 1889.

Application filed July 19, 1888. Serial No. 280,419. (No model.)

To all whom it may concern:

Be it known that I, JAMES MORRIS O'KELLY, a subject of the Queen of Great Britain, residing in the city, county, and State of New York, have invented certain new and useful Improvements in Automatic Vending Apparatus, of which the following is a specification.

This invention consists of an apparatus designed to operate automatically, so that by dropping a coin of a certain weight or size into the machine the article required is delivered, after which the mechanism is ready for repeating the operation, as hereinafter described and claimed. This result is accomplished by means fully described in the following specification and illustrated in the accompanying drawings, of which—

Figure 1 is a sectional view on the line 1, 1, Fig. 2; and Fig. 2 is a front elevation of the interior with parts broken away, the casing being in section.

A suitable case, 1, incloses and affords a support for a frame-work, 2, upon which the different parts of the apparatus are secured or mounted. Directly beneath an elongated opening or slot, 3, preferably located in the center of the top of the case 1, is secured a tube, 4, rectangular in cross-section, at the lower end of which and in line with its center is an open wheel, 5, mounted on the shaft 6, which latter has bearings in frame 2. Between the flanges of said wheel 5 are located the weight 7 and pins 8 in the positions shown in the drawings. Now it will be seen that by dropping the required coin into the slot 3 it passes through the tube 4 and falls between the flanges of wheel 5, striking obliquely on the weight 7, and from thence across the center of the wheel against one of the pins 8, when, by its preponderance of weight, it will cause the said wheel 5 to revolve until the pin 8 comes in contact with fixed stop 9 upon the case 1. The coin then escapes and falls from the wheel into the receptacle in the bottom of case 1. The weight 7 holds wheel 5 in this position until it is tilted back by the entrance of another coin. This wheel I shall hereinafter term a "tilting coin-receptacle."

50 A shaft, 10, also mounted on frame 2, carries at each end fluted disks 11, which constitute

the merchandise-ejector, the depressions being of a size to allow the article—such as cigars or cigarettes—to rest therein. An escapement, 12, on shaft 6 prevents the turning of the disks 11 (and consequently the discharging of the article) by engaging with one of a number of stops, 13, on the shaft 10, which are so arranged that by the partial rotation of the wheel 5 in either direction one of the stops, 13, is allowed to escape, while the escapement 12 moves into position to engage the next stop on the shaft 10 and so to prevent more than one article being discharged or delivered for each coin deposited.

Some trouble has been experienced in this class of machines from the bridging or jamming of the articles to be sold, thereby preventing their discharge or delivery into the vertical chute 12^a formed by the casing 1 and the inner plate, 2. To obviate this I use a device, as shown in the drawings. At one end of the lever 14, fulcrumed at 15, I mount a small roller, 16, which projects into the money-tube 4, so that by inserting the coin into the tube 4 the roller 16 is forced out, causing a second roller, 17, at the other end of the lever 14 to move in the cam-slot 18, formed in a wing, 19, set at right angles at what may be termed a "shaker" or "agitator," 20, pivoted at 21, and upon the oscillation of said lever the agitator is rocked on the pivot 21 and its inner portion thereby lowered and raised. On the said shaker or agitator 20, which projects into the feed-chamber 22, most of the weight of the articles rests, and upon its being lowered, as stated, the articles are prevented from jamming and bridging, and the increased weight upon the projection of the fluted disks 11 insures their movement when released by the escapement 12, thus allowing the article to drop into the chute 23, where it is accessible to the purchaser.

A spiral spring, 24, serves to bring the lever 14 back into its normal position and again raises the shaker or agitator and relieves the fluted disks from the weight of a portion of the articles.

Having thus described my invention, the following is what I claim as new therein and desire to secure by Letters Patent:

1. In an automatic vending apparatus, the

combination, with the casing having a coin-slot, of a tilting coin-receptacle, an escapement connected therewith, a merchandise-chute, and a merchandise-ejecting device arranged at the lower end of said chute and engaged by said escapement, substantially as set forth.

2. In an automatic vending apparatus, the combination of a coin-receptacle, an escapement attached to and operated by said receptacle, a chute for containing the merchandise, a shaft provided with fluted disks arranged in said chute, and stops on said shaft adapted to be engaged by the said escapement, substantially as and for the purposes set forth.

3. The combination, with the shaft 6 and the coin-feeding tube, of a tilting coin-receptacle mounted on said shaft, an escapement, 12, on said shaft, adapted to be operated by said receptacle, the shaft 10, and a merchandise-ejecting device having stops 13 mounted on said shaft and adapted to be engaged by said escapement, substantially as and for the purposes set forth.

25 4. In an automatic vending apparatus, the combination, with the casing having a coin-slot, of a tilting coin-receptacle, a merchandise-chute, a merchandise-ejector having fluted disks, and stops 13, arranged at the lower end 30 of said chute, and an escapement connected to and operated by said receptacle and adapted to engage said stops, as set forth.

5. In an automatic vending apparatus, the combination of a coin-receptacle, an escapement attached to and operated by said receptacle, a chute for containing the merchandise, an ejector arranged in said chute under the merchandise and adapted to be operated by the weight of the latter, and said ejector having stops adapted to be engaged by said escapement, substantially as set forth.

6. In an automatic vending apparatus, the combination of the tilting coin-receptacle, an escapement attached to and operated by said receptacle, a vertical chute for containing the merchandise, a shaft, fluted disks on said

shaft projecting into the lower part of said chute and adapted to be revolved by the weight of said merchandise, and stops on said shaft adapted to be engaged by said escapement, substantially as set forth.

7. In an automatic vending apparatus, the combination, with the coin-feeding passage and the shaft 6, of a tilting coin-receptacle mounted upon said shaft, a merchandise-chute, a merchandise-ejecting device consisting of fluted disks having points projecting into said chute, adapted to support the articles of merchandise between them, stops for locking said disks against rotation, and an escapement on shaft 6 for releasing said stops, substantially as set forth.

8. In an automatic vending apparatus, the tilting coin-receptacle consisting of a flanged wheel, 5, mounted on shaft 6 and having pins 65 8 8, in combination with a fixed stop, 9, substantially as set forth.

9. In an automatic vending apparatus, the tilting coin-receptacle consisting of flanged wheel 5, having pins 8 8 and weight 7, in 70 combination with a fixed stop, 9, substantially as set forth.

10. The combination, with the merchandise-feeding chute 22 and coin-feeding tube 4, of an agitator, 20, projecting into the merchandise-chute, and the lever 14, having operating-connection with said agitator at one end and projecting into the coin-feeding tube at the other end, substantially as and for the purposes set forth.

11. The combination, with the merchandise-feeding chute 22 and coin-feeding tube 4, of a pivoted agitator, 20, projecting into the merchandise-chute and connected with wing 19, having slot 18, and a pivoted lever, 14, 85 having a pin entering said slot and itself entering the coin-feed tube at its other end, substantially as set forth.

JAMES MORRIS O'KELLY.
